UNITED STATES PATENT OFFICE.

EGBERT M. FREESE, OF PLYMOUTH, AND JOHN W. WOLCOTT, OF FREMONT,
ASSIGNORS TO FATE & FREESE, OF PLYMOUTH, OHIO.

CUTTING-TABLE FOR BRICK OR TILE MACHINES.

SPECIFICATION forming part of Letters Patent No. 400,899, dated March 26, 1889.

Application filed November 14, 1888. Serial No. 290,842. (No model.)

To all whom it may concern:

Be it known that we, EGBERT M. FREESE, of Plymouth, in the county of Richland and State of Ohio, and JOHN W. WOLCOTT, of 5 Fremont, in the county of Sandusky and State of Ohio, have invented certain new and useful Improvements in Cutting-Tables for Brick, Tile, &c.; and we do hereby declare that the following is a full, clear, and exact description 10 of the invention, which will enable others skilled in the art to which it appertains to make and use the same, reference being had to the accompanying drawings, which form a part of this specification, and in which—

15 Figure 1 is a perspective view of our improved cutting-table, some of the cutting-wires having been removed to better show the construction of the machine. Fig. 2 is a top or plan view of the same. Fig. 3 is an end 20 elevation. Fig. 4 is a plan of the under side of the table and its appurtenances with the rollers removed. Fig. 5 is a vertical sectional view on the transverse plane indicated by the broken line marked $\alpha\alpha$ in Figs. 2 and 4; and 25 Figs. 6, 7, and 8 are detail views of parts which will be hereinafter more fully described.

Like letters of reference denote corresponding parts in all the figures.

This invention has relation to so called 30 "cutting-tables" for cutting brick, tile, and similar ware of clay or terra-cotta while in a plastic or "green" condition, as the column of clay which is to form said ware issues from the die or "former" of the press; and our improvement consists, essentially, in the combination, with the table carrying the devices 35 which support the advancing column of clay, of a revolving reel carrying a series of radially-arranged cutting-wires; also, in the 40 combination, with the revolving reel, of an automatically-operating gate; and, furthermore, in the detailed construction and combination of parts of the machine, as will be hereinafter more fully and at length set forth, 45 our improved machine being equally well adapted for use with a continuously-operating or "continuous-feed" press and with an intermittently-operating ("intermittent-feed") press.

50 Reference being had to the accompanying three sheets of drawings, the letter A design-

nates the roller-table, which receives the plastic column of clay or terra-cotta as it issues from the die of the press in the usual manner. This table (the detailed construction of which 55 will be described farther on) is supported adjustably upon standards B—one at each end—which are bolted to the floor, and provided at their upper ends with sockets b, through which the screw-threaded bearings C are inserted in 60 such a manner that these bearings may be raised or lowered at will without revolving in their sockets by turning the hand-wheels c, the threaded hubs of which engage the screws C. Each of these vertically-adjustable bearings carries at its upper end a fixed horizontal arm, D, the ends of which have cross-heads d, forming tracks or ways for the flanged rollers E E, which are connected to each other by an axle, e. These rollers or traveler-wheels 70 support the cross-heads f of the horizontal bearings F, so that it will be seen that said bearings have a limited forward-and-back motion in a horizontal plane upon the vertically-adjustable bearings D. 75

The movable bearings F at opposite ends of the machine are connected rigidly by a shaft, G, one end of which forms a journal for the hub H of the revolving cutter-reel. The latter consists of a series of radial arms, 80 I, preferably three in number, at equal distances from one another, and bent at right angles at their outer ends, parallel to the central shaft, G, as shown at J. These reel-arms I J may either be made in one piece, by bending a solid or tubular bar into the proper shape, or they may be made of two or more pieces, as expediency may direct. By preference we use sections of ordinary iron gas-pipe in their construction, which combines lightness with stiffness and durability, the two pieces or sections I and J being united at right angles to each other by elbows i. The free ends of the reel-arms are preferably, but not necessarily, connected endwise to one another by a ring or circle, K, having shaft G for its center and facing the press. As the column of clay issues from the die or former of the latter, it is received, as usual in this class of machines, upon a series of suitably-constructed rollers, L, which form the horizontal surface of the table, and are journaled 85 90 95 100

parallel to one another, and in sets consisting of a suitable number of rollers in each set, in the notched end pieces, M, of brackets N, Fig. 6, the inner ends of which are secured adjustably upon the fixed shaft G, from which they project at right angles. The attachment of said roller-brackets upon the shaft may be effected, as shown in the drawings, by means of collars m at the inner ends of the brackets, 10 provided on one side with binding-screws l, the inner ends of which bear against the fixed shaft G, so as to hold the brackets securely in their proper position.

Instead of the rollers L, the brackets M N 15 may support any other covering for the surface of the table, such as may be suitable to receive and preserve the form of the column of clay as it advances from the die of the forming-machine; and we do not confine ourselves to any particular device for this purpose.

To the horizontal arms of the revolving reel are fastened the outer ends of the cutting-wires O, the inner ends of which are suitably 25 fastened in hubs or sleeves P, which revolve between adjustable collars Q, fastened upon shaft G by means of binding-screws q.

We do not confine ourselves to any particular manner of attaching the wires to the reel- 30 arms and hubs, as this may be accomplished in various ways, but prefer to employ collars R, fastened adjustably upon arms J by binding-screws r; and provided on one side with a projecting socket-piece, S', Fig. 7, having a 35 square aperture for the insertion of a bolt, T, the squared lower end of which has a notch, t, in which the wire is fastened, while its cylindrical upper end is screw-threaded to engage the thumb-nut U. This device permits 40 of tightening the wire, so as to give it the proper tension for cutting, simply by turning the nut, and also enables the operator to substitute a new wire for a broken one in a moment of time.

45 The inner ends of the cutting-wires may be fastened upon their respective revolving hubs P by means of projecting T-shaped hooks p, or in any other convenient manner. It is obvious that the collars or bearings Q, between which 50 hubs P revolve, must be so spaced and secured upon the fixed shaft G relative to one another and to the bracket-collars m that each set of cutting-wires shall lie in a vertical plane intersecting shaft G at right angles.

55 At the end of the machine farthest from the press is arranged an automatic gate, V, Fig. 8, hinged upon a pintle, v, and operated by a spring, W, which, with the pintle round which the spring is coiled, is protected by a box or 60 casing, X. On that side which fronts the reel-arms I the gate is provided with a projecting segment, S, adapted to engage projections s upon the reel-arms I as the reel revolves. The tension of the gate-spring W operates to keep 65 the gate open, or in a position approximately parallel to shaft G; but as in revolving the reel its projections s successively strike and

engage the projecting segment S the gate will be closed—i. e., brought into a position at right angles to shaft G—in which position it is maintained until released as the reel projection slips past and disengages the segment, when the gate, actuated by its spring, instantly flies back to its open position. Obviously the gate V may be arranged to swing upward instead 70 of sidewise, so as to close by its own gravity, in which case the spring may be dispensed with, and when our table is used in conjunction with an intermittent-feed machine, where the ware is at rest while the cut is being made, 80 this gate may be omitted altogether.

From the foregoing description, taken in connection with the drawings, the manipulation and operation of our improved cutting-table will readily be understood. By means 85 of the vertically-adjustable bearings or supports it may speedily be adjusted in height to accommodate the different kinds or sizes of ware to be cut or different elevations of the “die” or former in different machines. The 90 revolving reel is so balanced that no more power than is necessary to cut the clay is required to operate it, and the roller-supporting bearings, with their appropriate brackets, are so divided in sets, it will be seen, as to admit 95 of the cutting-wire passing freely between them, so that the cut is always made while the wires pass downward or against the ware to be cut, the cutting-wires passing only once through the ware for each cut, thereby producing a clean cut and allowing the operator much more time to remove the ware from the table than is possible in that class of cutting-tables in which the cutting is done by a reciprocating frame provided with a series of 100 cutting-wires. A one-third revolution of the reel (where three arms are used) completes one cut and brings another set of wires into position for the next, the reel being always 105 revolved toward the operator.

As has been stated above, the gate at the forward end of the table operates automatically with the movement of the reel, and its object when used is to gage the length of ware, so that there is no waste or loss of time 115 in cutting off ends or trimming the ware; also, to arrest the advancing column of clay in order to hold it stationary while being cut, otherwise the cut would be slanting, which would necessitate dressing or finishing the 120 ware after leaving the table. As the table moves forward with the ware while the cut is being made and at the same ratio of speed, (when our table is used in conjunction with a continuous-feed press,) the cut will be clean 125 and square at all times. In case the cutting-table is intended for use with intermittent-feed machines, in which the movement of the plastic column of ware is stopped while the cut is being made, the traveler wheels or rollers E E may of course be omitted; but when used on a continuous-feed machine they will be used, for the reason that 130 the cutting-table has to be reciprocated at

each operation to prevent the ware being cut slanting.

Having thus described our invention, we claim, and desire to secure by Letters Patent 5 of the United States—

1. The combination of the table, revolving cutting-reel, and automatic gate, substantially as and for the purpose set forth.

2. The combination of the fixed vertically-10 adjustable standards or supports, the table, reel, and gate forming parts of and moving in unison with the table, substantially as and for the purpose set forth.

3. The combination of the fixed vertically-15 adjustable standards having horizontal bearings at their upper ends, the traveler-wheels adapted to run on said bearings, and the roller-table, reel, and gate supported on bearings resting upon the traveler-wheels, substantially

20 as and for the purpose set forth.

4. The combination of the fixed central shaft, adjustable roller-brackets, revolving cutting-reel, and revolving hubs for the attachment of the inner ends of the cutting-25 wires, substantially as and for the purpose set forth.

5. The combination of the fixed central shaft, adjustable roller-brackets, adjustable collars, and hubs adapted to revolve between the said collars and provided with means for 30 the attachment of the inner ends of the cutting-wires, substantially as and for the purpose set forth.

6. The combination of the revolving cutting-reel, the collars fastened adjustably upon 35 the horizontal reel-arms, and provided with means for attachment of the cutting-wires, the cutting-wires, the hubs forming means of attachment for the inner ends of the wires, the fixed reel-shaft, and the table, substantially 40 as and for the purpose set forth.

In testimony that we claim the foregoing as our own we have hereunto affixed our signatures in presence of two witnesses.

EGBERT M. FREESE.
JOHN W. WOLCOTT.
